APPARATUS FOR FILLING CONTAINERS

Ernest Henry Staber, Manhasett, N. Y., assignor
to Socony-Vacuum Oil Company, Incorporated,
New York, N. Y., a corporation of New York

Application June 27, 1933, Serial No. 677,775

4 Claims. (Cl. 226—102)

This invention relates broadly to machines capable of delivering simultaneously a multiple of measured quantities of liquid to cans, barrels, drums, or similar containers. More specifically 5 it relates to improvements to machines of this type, which improvements are designed to permit of more adequately handling vapors arising from the liquid handled, to permit of increased speed in the filling operation, to permit of increased facility in handling containers, and to 10 increase the accuracy of measurement of the liquid handled.

Machines have heretofore been devised in which a multiple of measuring compartments are 15 simultaneously filled, and subsequently simultaneously emptied into a series of containers. After emptying, the measuring compartments are again refilled, while the filled containers are removed and empty ones placed in position to receive their charge. Machines of this type have 20 been designed to measure the filling charge by volume only, or by a method which combines measurement of weight and volume. The improvements herein disclosed are capable of being applied to both classes of machines above 25 described. The disclosures herein contained are discussed in their application to a machine designed for use with gasoline, but the limitation of the discussion thereto is merely for convenience and simplification, and it must be understood that I may use these devices when and wherever applicable, without restriction as to kind of liquid handled or general kind of machine to which they are attached. For instance, 30 the problem of recovery of vapors reaches not only gasoline, but extends to any and all volatile liquids with equal pertinence. In some cases, it is conceivable that complete and safe recovery of vapors might be of far more importance 35 than mere cost of product otherwise lost, for instance in the handling of volatile liquids whose vapors are markedly toxic.

In the former practises of which I am aware, many devices have been made use of which 45 tempted the solution of some of the problems herein met, but in no case have I found these solutions completely made with the minimum of equipment and cost and certainty of function herein attained.

50 Among the objects of this invention are the development of means for preventing the escape of vapors from the liquid handled by setting up a closed system embracing all points of liquid and vapor transfer, and the provision of easily man- 55 aged, simple, and effective means for so doing.

A further object is the provision of means for speedily accomplishing accurate measurement both by weight and by volume.

Further objects comprise the provision of devices for quickly and effectively handling containers, and such other objects and advantages as may appear hereinafter. 5

To permit of more readily understanding the improvements in their several parts in connection with their industrial applications, there are 10 attached to and made a part hereof several drawings.

In these drawings:

Figure 1 is an elevation of a weight-measuring filling machine. 15

Figure 2 is a side view of the above machine.

Figure 3 is an elevation of a volume-measuring filling machine.

Figure 4 is a side view of the above machine.

Figure 5 is a section of one type of vapor recovery nozzle. 20

Figure 6 is a section of a modification of the vapor recovery nozzle.

Figure 7 shows a temperature volume calibrating device. 25

Figure 8 shows a can handling mechanism.

Figure 9 shows a side view of the above can handling mechanism.

Figure 1 shows a weight measuring filling machine. That is to say, it shows a machine of the 30 class wherein the amount of liquid delivered to the container is determined by weight. Figure 2 is a side view of the same machine, with like parts bearing identical numerals, and it will materially assist in the understanding if Figures 1 and 2 are 35 read together. Essentially it consists of a multiple container 1, divided interiorly by partitions 2 into a series of compartments of equal volume. The container 1 is suspended by links 3 from a system of levers 4—4 which suitably transmit 40 forces to a scale beam 5 whereby after suitable taring which may or may not be permanently set off, the weight of liquid charged to the container 1 is determined. The container 1, through the weighing mechanism 3, 4, 5 and links 6, is suspended from a suitable frame composed of members 7—7 etc. 45

A main liquid supply pipe 8 is mounted upon the upper portion of the frame 7—7, and, if desired, may be so mounted as to contribute materially 50 to the rigidity and stability of the frame. In the present instance it is so mounted. Extending downwardly from the pipe 8 is a smaller pipe 9, having intermediate its ends a valve 10, of the quarter-turn quick opening type, the stem of 55

which is extended by bar 11 through bearing 12 to the outside of frame 7, and terminates in a handle or crank 13 of suitable length. Pipe 9 terminates at its lower extremity in a filling neck 14. Now 14 is solidly affixed to frame 7-7, and communicates to container 1, which is movable with respect to frame 7-7. Between these two there must be a vapor tight joint of a type which will not interfere with the accuracy of the weighing operation. To answer this necessity, I have made use of an annular cup 15, upturned around the bottom of neck 14, and this cup I fill with mercury or other suitable liquid, as shown at 16. Into this liquid seal cup the inner ring 17 of cap 18 is allowed to dip. Cap 18 is rigidly fastened to the cover of container 1. As the weight of the mercury 16 is supported directly by pipe 4, etc., the only error of weighing introduced is that inconsequential one due to the buoyancy of that part of neck 17 which is submerged in the mercury. Container 1 is composed of a cover portion made up of sections 19, and a lower portion 20. These may be of any suitable construction, and in the form shown the cover sections are of cast iron and the lower portion is of welded sheet iron. Within the lower portion 20, are partitions 2, dividing the container into a suitable number of compartments, in the present case into 6. To compensate for errors in placing the partitions 2 and other unavoidable errors influencing the volume of the compartments, volumetric adjustment is obtained by the use of device 21. The lower end of 21 is wedge shaped to permit of finer adjustment, and the device is suspended by rod 22 which is threaded or otherwise adapted to be positioned to suspend 21 to a variable depth within the compartment. In filling, the proper weight is set off on scale 5, and the liquid allowed to enter until the device balances. The liquid level will then be slightly above the top of partitions 2 and the amount in each compartment is equalized by compensators 21. Once the position of the compensators has been fixed so that the amounts delivered by each of the compartments are equal, the adjustment may be permanently fixed, as by spot welding rod 22 to cap 19. At the bottom of each compartment is a valve 23, delivering into a nozzle 24. The valves 23 are of the quarter-turn quick opening type, and each is equipped with a handle 25, which is extended to a bar 26 and pivotally connected thereto. The valve 23 at the right hand end of the assembly shown in Figure 1, which is the operating end, is equipped with a second handle 27, operation of which, through bar 26 and handles 25, results in simultaneous opening and closing of all valves 23. The detailed construction of nozzles 24 is separately shown in Figure 5 which is later explained. From the side of each nozzle 24 there arises a pipe 28 which receives vapor from nozzle 24 in a manner later explained. This pipe 28 is shown fully on the left hand nozzle of Figure 1, being omitted elsewhere for clarity. Each of these pipes 28 communicates with a horizontal pipe 29, partially shown, and the vapors collected in manifold 29 rise through pipe 30 and pass into the interior of container 1 by way of a check valve 31 of known type. Vapors from the interior of container 1 pass out through opening 32 in filler neck 14 and thence through pipe 33 which communicates with the closed top tank, not shown, from which the original supply of liquid is withdrawn to pipe 8. In this manner the air present in cans 34 when filled interchanges place with the liquid in container 1, and when container 1 is

filled, passes to the original storage tank. In this manner, escape of vapors to the atmosphere is minimized, and if the storage tank be under a slight vacuum, is prevented entirely.

Figures 3 and 4 are front and side views, respectively of a volumetric filling machine with corresponding parts carrying like numbers, and should for clarity be read together. A frame, 35, 35, 35, supports a multiple of volumetric measuring containers, 36, 36, two being used in the particular machine shown. A filling line, 37, connects with a closed supply tank, branches and communicates through valves 38 with containers 36. Valves 38 are suitably fastened together for simultaneous operation in the usual apparatus, although the connection is omitted here for simplicity.

Containers 36, are of cylindrical form, with conical top and bottom and are preferably fabricated of sheet steel, welded. From the bottom of each container a pipe 39 extends downwardly through a discharge valve 40, and continues to a filling nozzle 41. Upwardly from each container 36 there extends a pipe 42 and at a predetermined point in this pipe 42 there is inserted an overflow line 43, (shown in the side view, Figure 4), having in it a sight box of glass 44, and continuing to an overflow tank 45. A supplementary overflow line 46 is installed above line 43 as shown. This line also serves to return vapors from overflow tank 45 to the upward extension of line 42, which communicates to the closed storage tank from which liquid is primarily withdrawn. In order that the overflow tank may be drained from time to time, valved line 47 is provided. The filling volume of containers 36 extends from discharge valve 40 to overflow pipe 43. In order to adjust the volume therein contained, a threaded collar 48 is installed on the side of each container 36 and a threaded plug 49 is inserted therein. This is forced into the container until the volume is correct, and then, if desired, may be secured as by welding. Certain modifications of this calibration device are later explained in connection with Figure 7.

Passing through valves 40, which are preferably arranged for simultaneous operation, although the connection is here omitted for simplicity, the liquid passes to containers (not shown) through nozzles 41. These nozzles are later described in detail in Figure 6, and for the present will be described as having a fixed portion 50, and a movable portion 51 which may be lowered to effect closure with the can. A suitable cam and lever device, such as that shown at 52, serves to operate the movable portion. From the fixed portion 50, vapors from the can pass out through check valves 53 into line 54 which communicates with the upward extension of line 42, so that gases from the filling cans may pass into the emptying containers 36, and when the containers are being filled, may pass back to the tank from which liquid is being drawn.

Figure 5 shows a sectional view of nozzle 24 as used on the weight filling machines. It is essentially composed of a body of brass, aluminum, or other suitable material, having the shape of a combined cylindrical section and frustro-conical section. Prior devices have attempted to get vapor tight connections between container and nozzle by gaskets pressed against the can top, as in Smart, U. S. Patent 1,138,511, but these have always failed, due to flexibility of the can top and other reasons. Inasmuch as the can top, whether

a neck is affixed to it at the time of filling or not, affords a circular opening with line contact as indicated at 55—55, I have found that the frustro-conical shape of nozzle, passing from a diameter 5 less than that of the filler hole to one greater, together with a properly applied pressure will give a vapor tight joint with a maximum of simplicity and efficiency. The nozzle 24 is found to provide an inner sleeve 56 forming a liquid passage communicating with the pipe 57 which leads from the measuring container, and an outer sleeve 58 which defines a gas or vapor passage annularly disposed around sleeve 56 and communicating through pipe 28 with the vapor disposal system.

Figure 6 shows a sectional view of the nozzle 41 preferably used in connection with the volumetric filling machine. This nozzle consists essentially of a movable portion 51 and a fixed portion 50. Depending from the fixed head 50 are two cylindrical sleeves, 59 and 60. The movable portion 51 consists of three cylindrical sleeves, 61, 62, and 63, 61 and 62 being spaced apart by integrally cast bars 64, and 63 being joined at the bottom with 62 to form an annular cup. Lips 65 and 66 are affixed respectively to the lower ends of sleeves 61 and 62, and form a frustro-conical nozzle tip of the same nature as before referred to. The inner surface of sleeve 61 is machined, guiding and allowing the body 51 to move reciprocably with body 50. Liquid passes downward through sleeves 59 and 65, and vapors pass upwardly through the annular passage around the outside of sleeves 65 and 61, to be collected in the chamber of head 50 and passed to vapor system through opening 67. To provide a liquid seal, the annular cup between 62 and 63, into which 60 dips, is partially filled with a suitable liquid such as mercury. Proper bosses, not shown, are cast on the outer surface of 63 to provide for attachment 40 of the operating levers. This nozzle can be used also on machines of the type shown in Figures 1 and 2, where it yields considerably more flexibility than the simpler type of nozzle shown in Figure 5.

The methods of filling vary, the two most usual being filling with a weighed amount of liquid or filling with a standard volume. Due to the fact that liquids expand with rise in temperature and filling must often be accomplished at temperatures different from that at which the liquid should be measured, a temperature-compensating volume calibrator must be used. To accomplish this purpose, I make use of the construction shown in Figure 7. To the wall 68 of the container, a flanged neck 69 is attached. This flanged neck 69 is machined to provide a packing recess 70, and receive a packing follower 71. Within the flanged neck, the cylindrical calibrator 72 may be moved back and forth. Attached to the flanged neck 69 is a yoke 73 and hand wheel 74, of the type commonly used on rising stem valves, working on a threaded stem 75 which is fixed into calibrator 72 and serves to extend it into the tank to a greater or less degree. Attached to the body of the calibrator 72 is a pointer 76, travelling over a scale 77, affixed to one side of the yoke 73. The scale is graduated in temperature degrees, and is used as follows: A thermometer is permanently placed at some convenient place in the filling line, and the temperature of the liquid noted. If it is 60 degrees F., and the standard temperature is 60°, the calibrator is placed at 60 degrees and the volume measured is correct. If the temperature be 70 degrees F., then the pointer is set at 70 degrees and the volume will be correct when

cooled to 60 degrees F. In other words, an amount can be delivered at any temperature which will be the correct volume when measured at the standard temperature of 60 degrees F. Of course any standard temperature of filling can 5 be adopted, and the method be similarly used.

Figures 8 and 9 are respectively front and end views of a can handling mechanism adapted for use with the weighing type of multiple filling machine. Like numerals are used on the same 10 parts in both views, and for easier understanding the two figures should be read together.

In these figures 1 denotes main frame members of the filling machine, and 18 denotes the base castings of that frame. Above the frame, at a 15 suitable distance, there is a roller conveyor, designated by 78—79. This conveyor may be inclined, as shown, or level. Extending upward from base castings 18 are end posts 80, which are shown in dotted lines in Figure 9. Extending between end 20 posts 80 are bars 81, the front one of which is removed for clarity in Figure 8. Attached to the rear bar 81, there is a series of vertical bars 82 and a horizontal bar 83 to assist in accurately 25 positioning the cans 34. This structure may be of any desirable nature and is omitted in Figure 8. Regularly disposed upon castings 18, at points corresponding to the center of each can 34, there are vertical cylinders 84. Within each of these cylinders 84, there is a plunger 85. Each plunger 30 85 carries a table 86, and each table 86 carries several plates 87, the combination of 86 and 87 being assembled from such cast shapes or other forms as seems desirable. The tables 86 are secured to plunger 85 by a threaded joint and set 35 screw, as indicated at 88. The tables 86 by means of the fingers or plates 87, which extend through the conveyor 78—79 between the rollers, is adapted to move vertically, lifting the cans away 40 from the roller conveyor, and holding them against the nozzles until filled, and then depositing them on the conveyor again. This movement is accomplished by lever 89, shown in side view, Figure 9, which operates about a pivot 90, placed in arms 81 which extend from the rear of cylinders 45 84 on either side of a vertical slot indicated by dotted lines at 92—92. End 93 of lever 89 is engaged in a slot indicated by dotted lines 93¹ and plunger 85. Upon the outer end of lever 89 is fixed a counterweight 94 of sufficient weight to 50 more than counterbalance a filled can and hold it securely against the vapor saving nozzle until it is desired to release it. Midway of the lever 89 is a roller 95, resting upon a cam 96, mounted on shaft 97. Shaft 97 carries a gear 98 at its right 55 hand end, Figure 8, which meshes with a gear 99 on shaft 100. Shaft 100 carries gear 101 which meshes with worm 102, carried on shaft 103. Shaft 103 is operated by bevel gears 104, driven from hand wheel 105. Operation of this hand 60 wheel, through cams 96, levers 89 and plungers 85 serves to lift and lower the cans 34 as desired.

In the above description, the conveyor is an inclined roller conveyor. In practice, many types of can handlers, such as shuttles, turntables, slat 65 and roller conveyors are used, and my device is capable of being modified for use with any of these without departing from the essentials of the embodiment here shown.

While the weight type machine, the volumetric 70 machine, various types of nozzles, calibrating device and can-handling mechanism have been described separately, it is obvious that they are all parts of the same development, and any of the improvements can be used in company with any 75

others, or can be used in connection with machines of prior types, and any single one of the improvements so used, or any combination of them so used is considered to be within the scope of the invention if within the scope of the following claims.

I claim:

1. In a system for simultaneously filling a plurality of liquid containers, a closed storage tank from which liquid is withdrawn, a suspended multiple measuring vessel into which such liquid is discharged, a filling pipe to effect such discharge, a weight balancing mechanism for measuring amount of such liquid, multiple valves controlling multiple outlets from said multiple measuring vessel, means upon each of such multiple outlets to effect a vapor tight closure with a container to be filled, means whereby air from said container may be vented to said multiple measuring vessel, means whereby vapors from said measuring vessel may be vented to said closed storage tank, and means effecting a vapor tight joint between said measuring vessel and said fill pipe in a manner which allows accurate operation of said weighing mechanism.
2. A nozzle for vapor-proof can filling machines and the like, comprising fixed and movable portions; the fixed portion having a central tube through which liquid may flow, a skirt surrounding said central tube and spaced therefrom to define a vapor collecting space, and an outlet through which vapors may be removed; the movable portion having a central tube adapted to surround the central tube of the fixed portion and to move thereon in a direction parallel to the common centerline, a nozzle having a liquid passage extending from the central passage of the movable portion, an annular vapor passage surrounding said nozzle and communicating with a vapor space surrounding the central tube of the movable portion, a shell defining said annular passage and having externally the shape of a conical frustum, an annular cup attached to said shell and surrounding said vapor space, said cup being adapted to contain a sealing liquid into which the skirt of the fixed portion may dip.

3. In a machine for multiple filling of liquid containers, of the type characterized by measurement of charge by weighing, a source of liquid, a freely suspended charge receiving vessel, a fixed pipe whereby such vessel may be filled, means effecting a vapor tight joint between said fixed pipe and said measuring vessel which do not impose a variable load on said weighing means, a plurality of discharge nozzles designed to cooperate between said measuring vessel and containers to be filled, means whereby vapors displaced in filling said containers may pass to said measuring vessel, means whereby vapors may pass from said measuring vessel to the source of liquid, a conveyor independent of said measuring vessel whereon containers may be moved to and from a position below said measuring vessel, means independent of said conveyor adapted to raise containers therefrom into a filling position in contact with said discharge nozzles, to maintain such position until containers are filled, and to again deposit containers on said conveyor when filled.

4. In a machine for multiple filling of liquid containers, a source of liquid, a measuring vessel, a volume adjusting device cooperating with such vessel, a discharge nozzle adapted to connect such vessel to a container to be filled, said discharge nozzle consisting of a fixed part attached to the vessel and a movable part reciprocally movable upon said fixed part, both parts having mutually coextensive central liquid passages and annular vapor passages, said movable part terminating in a nose having the external shape of a frustum of a cone adapted to engage a container orifice in line contact, said movable part cooperating with said fixed part to form a liquid seal whereby vapors are prevented from escaping from said coextensive annular vapor passages, means passing vapors from said coextensive annular passages to said measuring vessel, means passing vapors from said measuring vessel to said source of liquid, and means adapted to lower the movable portion of said nozzle into positive contact with a container and to raise it away from said container when filling operation is completed.

ERNEST HENRY STABER.
